(57) CLAIM

The ornamental design for swimwear, as shown and described.

DESCRIPTION

FIG. 1 is a perspective view of swimwear;
FIG. 2 is a rear perspective view thereof;
FIG. 3 is a front elevational view thereof;
FIG. 4 is a rear elevational view thereof;
FIG. 5 is a top plan view thereof;
FIG. 6 is a bottom plan view thereof;
FIG. 7 is a right side elevational view thereof;
FIG. 8 is a left side elevational view thereof;
FIG. 9 is a front perspective view thereof with top pulled out;
FIG. 10 is a rear perspective view thereof with top pulled out;
FIG. 11 is a front perspective view thereof with middle flap folded down over bottom half; and,
FIG. 12 is a rear perspective view thereof with middle flap folded down over bottom half.
The broken lines in the figure views depict stitching, which does form a part of the claimed design.

1 Claim, 12 Drawing Sheets
